Attorney

UNITED STATES PATENT OFFICE.

JOSEPH WILLIAM GUIMONT, OF MONTREAL, QUEBEC, CANADA, ASSIGNOR OF ONE-HALF TO MENDOZA LANGLOIS, OF MONTREAL, QUEBEC, CANADA.

RADIATOR.

Application filed December 19, 1921. Serial No. 523,504.

To all whom it may concern:

Be it known that I, JOSEPH WILLIAM GUIMONT, a British subject, residing at 24 St. Antoine Street, in the city of Montreal, Province of Quebec, Dominion of Canada, have invented certain new and useful Improvements in Radiators; and I hereby declare that the following is a true, clear, and exact description of the same.

10 The present invention relates to improvements in radiators and is fully described in the following description and accompanying drawings, in which:

Figure 1 is a side elevation of a radiator according to the invention.

Figure 2 is an enlarged longitudinal sectional view through one of the radiator sections.

Figure 3 is a cross section on line 3-3 of Figure 2.

Like numerals of reference indicate corresponding parts in each figure.

Referring to the drawings:

1 is the outer casing of one of the sections 25 of a radiator having intermediate thereof two central vertical walls 2, extending to a portion adjacent the upper and lower ends of said outer casing, said walls 2 being closed at their upper and lower ends by the 30 horizontal walls 3. 4 are walls extending centrally across the outer casing in its upper and lower ends. Between said walls 3 and 4 are provided the inlets and outlets 5 and 6, respectively. The outer casing 1, the 35 walls 2, 3 and 4, are preferably cast in one piece. When the outer casing 1 is cast, two vertical parallel elongated open end passages 7 and 8 respectively are formed, in

each of which are mounted the tubes 9 parallel to said walls which are preferably of 40 smaller diameter than the said passages 7 and 8, in order to provide a passage 10 in between the walls 1 and 2. The tubes 9 are provided at each end thereof with an outwardly projecting circumferential flange 11, 45 which is adapted to fit snugly in between the inner sides of the walls 1 and 4, said flange being preferably welded or otherwise secured to the inner sides of said walls, so as to form a watertight joint.

It will readily be seen that a relatively narrow passage or space 10 will be provided between the walls 1, 2 and the inner tubes 9, providing a relatively large radiating surface with a very thin water column.

In the drawings is illustrated the particular method of welding the inner tubes to the casing, but this method is described and claimed in my co-pending application.

What I claim as my invention is—

A radiator section comprising an outer casing provided with openings; horizontal central walls at each end of said casing; tubes arranged parallel to said casing and provided with a flange at each end, each of said flanges being adapted to snugly fit against the inner side of the outer casing and the inner side of said central wall; and V shaped securing means for fastening said tubes in place.

Signed at Montreal, Quebec, Canada, this 2nd day of December, 1921.

JOSEPH WILLIAM GUIMONT.
